UNITED STATES PATENT OFFICE

WILLIAM ALLEN SMITH, OF MANCHESTER, ENGLAND, ASSIGNOR TO PNEUMATIC CONVEYANCE & EXTRACTION (1929) LIMITED, OF LONDON, ENGLAND, A COMPANY OF GREAT BRITAIN

ROTARY SEPARATOR

Application filed October 31, 1927, Serial No. 230,046, and in Great Britain November 8, 1926.

This invention relates to rotary separators and in particular to separators for extracting from air or gases, dust or like finely divided material in suspension.

According to this invention the rotary separator comprises a receiving or collecting bunker having an upper separating space or chamber, an inlet to the collecting bunker and an outlet from the separating space or chamber surrounded by an annular ring in which is rotatably mounted a high speed rotor covering such outlet, comprising a perforated member (disc or cone) and a plurality of centrifugal elements or vanes closely associated, and rotating, with the perforated member and shaped to produce a counter pressure to the passage of the air or gases to the outlet. Other features of the invention lie in the details of construction of the improved rotary separator as described and claimed.

Upon the accompanying drawings, Fig. 1 is a longitudinal sectional elevation, and

Fig. 2 is a transverse sectional elevation of one form of rotary separator made in accordance with this invention.

In the example illustrated in Figs. 1 and 2, the separator is applied to pneumatic conveyance apparatus for separating the fine suspended matter from the air to prevent it from reaching the exhauster. The separator mechanism is arranged in one end of the separating space or chamber *a* above the receiving or collecting bunker *b* and in the mouth of the exhauster pipe *c* and comprises a high speed rotor consisting of a centrifugal element and a circular perforated disc *e* having a large number of small holes and is mounted on a horizontal shaft *g* arranged substantially axially of the mouth of the exhauster pipe *c*. The centrifugal element consists of a fan like disc having a number of blades or vanes *h* bent to give when rotating a counter pressure to the outward passage of the air. This centrifugal element is arranged on the outer or impact face of the perforated disc. The disc *e* runs in an annular channel or ring *k* secured to the end of

the casing *a* around the mouth of the outlet pipe *c*.

An auxiliary outlet pipe *f* may be provided from the annular ring *k* and extending to the bottom of the collecting bunker or into a separate collecting bunker, to allow of the escape of any solid material which may collect in the ring. Baffle plates *m* and *n* are provided, in the separator and above the inlet *o* for the conveying air, so as to partition off the separating space from the collecting bunker and to effect the initial deposition of the suspended solid matter into the collecting bunker *b* before reaching the rotary disc, and so that the disturbance caused by the rotating disc will not materially interfere with such deposition or with the deposited matter in the bunker.

In operation, the conveying air enters by the inlet *o* of the collecting bunker *b* and discharges the greater part of the material, which falls by gravity into the bunker. This air is however, still heavily charged with a fine impalpable powder in suspension and rises from the bunker between the baffles *m* and *n*.

This air is then drawn past the perforated deflector disc *e* passing through or around the edge of same, which is meanwhile rotated at a suitable high speed and the solid particles in the air impinging on the vanes *h* or on the solid parts of the disc receive a rotary or tangential motion and are projected radially or tangentially by centrifugal force back into the separating chamber or into the annular channel surrounding the separator discs, the cleansed air alone passing through to the exhauster by the pipe *c* while the solid matter falls between the baffles into the collecting bunker. An outlet pipe for any of the fine separated material which may collect in the annular channel is provided and is led down to a point adjacent to the bunker outlet so that such fine material may be drawn off with the other and heavier material in the bunker.

Such an arrangement of the outlet prevents air from being drawn back into the annular channel or air space, which would partly defeat the action of the separator. Further, a

suitable non-return flap or other valve may be provided in such pipe.

The deflector member of the separator may have any number of discs or pairs or sets of them or may only consist of one disc as shown according to the nature of the work for which it is required, and instead of small perforations, radial slots or other relatively large openings may be used where the circumstances permit, or make it desirable.

In a modified form of the separator one or more cones are employed in place of the discs, which cones may be arranged in either direction.

15 The various forms of the deflector member may obviously be used in combination as well as separately and each constitutes a simple and effective separator. The axis of the revolving element of the deflector may be horizontally, vertically or angularly arranged.

Though its main use is in connection with pneumatic conveyance apparatus for preventing the fine suspended impalpable dust from reaching the exhaust, which dust is so destructive to the bearings and reciprocating parts thereof, the separator may also be used for other purposes, as for instance in purifying air, for the extraction of grit from flue gases and for similar purposes.

30 The arrangement of the perforations or vanes in the discs or cones is open to modification to suit the purpose for which the separator is required, so also is the shape of the rotating element, for example, a hemispherical element may be used and inclined, spiral or tangentially arranged vanes may be employed.

The improved separator is more efficient and compact than other forms of separators hitherto proposed and in particular as compared with the rotary drum type of separator many of the difficulties, for instance, as regards the creation of vortices which remain unbroken do not arise.

45 What I claim is:

1. A rotary separator adapted to be installed in a pneumatic conveyance system for extracting from air or gases passing through it, dust or like finely divided material in suspension, comprising a receiving or collecting bunker having an upper separating space or chamber, an inlet to the collecting bunker, an outlet from the separating space or chamber, baffles between the collecting bunker and the separating space or chamber, a perforated deflector member rotatably mounted adjacent to the said outlet, through or past which member the air or gases have to pass out from the casing, rotary impact members associated with the said deflector member to produce a counter pressure to the normal passage of the gases through or past the said deflector member, and means for driving the deflector member, as set forth.

65 2. A rotary separator adapted to be in-

stalled in a pneumatic conveyance system for extracting from air or gases passing through it, dust or like finely divided material in suspension, comprising a receiving or collecting bunker having an upper separating space or chamber, an inlet to the collecting bunker, an outlet from the separating space or chamber, an annular ring within the separating chamber and over the outlet, baffles between the collecting bunker and the separating space or chamber, a perforated deflector member rotatably mounted within the said annular ring, through or past which member the air or gases have to pass out from the casing, rotary impact members associated with the said deflector member to produce a counter pressure to the normal passage of the gases through or past the said deflector member, and means for driving the deflector member, as set forth. 70 75 80 85 90

3. A rotary separator adapted to be installed in a pneumatic conveyance system for extracting from air or gases passing through it, dust or like finely divided material in suspension, comprising a casing having an upper separating space or chamber, a collecting bunker below said space or chamber, baffles between the separating space or chamber and the bunker, an inlet below one of the baffles, an outlet from the separating space or chamber, an annular ring surrounding said outlet, a perforated disc rotatably mounted in said ring, a fan element secured to said disc the blades of which are arranged to produce a counter-pressure to the normal passage of the air or gases through or past the disc, and means for driving the fan, as set forth.

In testimony whereof I have signed my name to this specification.

WILLIAM A. SMITH.
